UNITED STATES PATENT OFFICE.

CHRISTIAN W. MEINECKE, OF NEW YORK, N. Y.

DESIGN FOR A BOTTLE.

SPECIFICATION forming part of Design No. 25,471, dated May 12, 1896.

Application filed March 7, 1896. Serial No. 582,271. Term of patent 3½ years.

To all whom it may concern:

Be it known that I, CHRISTIAN W. MEINECKE, a citizen of the United States of America, and a resident of the city, county, and State of New York, have invented and produced a new and original Design for Atomizer-Bottles, of which the following is a specification.

Figure 1 represents a front elevation. Fig. 10 2 represents a plan view of the same.

The leading feature of my design consists in a spheroidal-shaped globular chamber, forming the base of the bottle. The crown of this chamber is integral with a cylindrical wall band or panel whose diameter is much smaller than the globular chamber referred to. Said cylindrical wall band or panel is also integral with an upper and smaller chamber, which is also spheroidal in shape and integral with the 15 crown thereof, and is provided with a flat circular disk from which arises an externally-

screw-threaded neck. The surface of the cylindrical wall band or panel may have inscribed thereon any suitable words.

In the drawings, A represents the lower 25 spheroidal-shaped globular chamber integral with the cylindrical wall band or panel B, which in turn is integrally connected with the upper and smaller globular-shaped chamber C and provided with the flat circular disk D, 30 from which arises the external screw-neck E.

What I claim is—

The design for an atomizer-bottle substantially as shown and described.

In testimony that I claim the foregoing as 35 my invention I have signed my name, in presence of two witnesses, this 5th day of March, 1896.

CHRISTIAN W. MEINECKE.

Witnesses:

JULIAN A. HURDLE,
D. S. DOLBEAR.
